US00D677780S

(12) **United States Design Patent**
Choi et al.

(10) **Patent No.:** US D677,780 S
(45) **Date of Patent:** ** Mar. 12, 2013

(54) **FILTER CARTRIDGE**

(75) Inventors: **Dong-II Choi**, Kyoungi-Do (KR);
Kyoung-Ho Lee, Hwaseong-Si (KR);
Jin-Ho Lee, Seoul (KR); **BongHyup Kang**, Seoul (KR); **Dong-Sun Noh**, Bucheon-Si (KP)

(73) Assignee: **3M Innovative Properties Company**,
St. Paul, MN (US)

(**) Term: **14 Years**

(21) Appl. No.: **29/389,722**

(22) Filed: **Apr. 15, 2011**

(51) **LOC (9) Cl.** 29-02

(52) **U.S. Cl.** **D24/110.1**

(58) **Field of Classification Search** D24/110-110.2;
128/206.12-206.27, 207.11

See application file for complete search history.

(57) **CLAIM**

The ornamental design for a filter cartridge, as shown and described.

DESCRIPTION

FIG. 1 is a perspective view, showing the new design for a filter cartridge;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing forms no part of the claimed design.

1 Claim, 3 Drawing Sheets

FIG. 1

FIG. 2

FIG. 3

FIG. 4

FIG. 5
